UNITED STATES PATENT OFFICE.

GEORGE HOWE, OF NEW YORK, N. Y.

DESIGN FOR AN ELECTRICALLY-ILLUMINATED SIGN.

No. 38,014.

Specification for Design.

Patented May 15, 1906.

Application filed March 29, 1906. Serial No. 308,793. Term of patent 7 years.

To all whom it may concern:

Be it known that I, GEORGE HOWE, a citizen of the United States, residing at New York, in the county of New York and State of New York, have invented a certain new, original, and ornamental Design for Electrically-Illuminated Signs, of which the following is a specification, reference being had to the accompanying drawing, forming part hereof.

The figure is a plan view of an electrically-illuminated sign, showing my new design.

I claim—

The ornamental design for an electrically-illuminated sign, as shown.

GEORGE HOWE.
